CLAIM

The ornamental design for a television receiver, as shown and described.

DESCRIPTION

FIG. 1 is a front perspective view of a television receiver, showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof;
FIG. 9 is an enlarged view of the encircled portion in FIG. 4;
FIG. 10 is an enlarged view of the encircled portion in FIG. 5;
FIG. 11 is an enlarged view of the encircled portion in FIG. 6;
FIG. 12 is an enlarged view of the encircled portion in FIG. 7; and,
FIG. 13 is an enlarged view of the encircled portion in FIG. 8.
The even-dash broken lines illustrating portions of the television receiver form no part of the claimed design. The dot-dot-dash broken lines encircling enlargement portions of the claimed design form no part of the claimed design.

1 Claim, 13 Drawing Sheets
